CLAIM

The ornamental design for a package suitable for temporarily storing contact lenses, as shown and described.

DESCRIPTION

FIG. 1 is a top perspective view of a package suitable for temporarily storing contact lenses showing our new design where a lid is open;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof;

FIG. 7 is a bottom plan view thereof;

FIG. 8 is a cross sectional view taken along line 8-8 of FIG. 6;

FIG. 9 is a cross sectional view taken along line 9-9 of FIG. 6;

FIG. 10 is a top perspective view of the package suitable for temporarily storing contact lenses of FIG. 1 where the lid is closed;

FIG. 11 is a front elevational view thereof;

FIG. 12 is a rear elevational view thereof;

FIG. 13 is a left side elevational view thereof;

FIG. 14 is a right side elevational view thereof;

FIG. 15 is a top plan view thereof; and,

FIG. 16 is a bottom plan view thereof.
